UNITED STATES PATENT OFFICE.

ANDREW B. MORRISON, OF LITCHFIELD, ILLINOIS.

HOISTING-DERRICK.

SPECIFICATION forming part of Letters Patent No. 297,831, dated April 29, 1884.

Application filed February 6, 1884. (No model.)

To all whom it may concern:

Be it known that I, ANDREW BROWN MORRISON, a citizen of the United States, residing at Litchfield, in the county of Montgomery 5 and State of Illinois, have invented certain new and useful Improvements in Hoisting-Derricks, of which the following is a specification, reference being had therein to the accompanying drawings.

10 My invention relates to certain new and useful improvements in portable tripods or derricks for lifting heavy weights.

The object of my invention is to lift rock or heavy weights, when desirable, from the 15 surface of the earth onto wagons or cars for transportation, or to raise rock or mineral from mines by means of a portable tripod or derrick. I attain these objects by means of the peculiar construction and arrangement 20 of the various parts of my device, which will be more fully pointed out and described in the specification and claims, reference being had to the drawings accompanying this application and forming part of the same, in 25 which—

Figure 1 is a side elevation of my invention, showing frame expanded and weight raised. Fig. 2 is an end elevation of the same, and Fig. 3 shows detail views of same.

30 Similar letters refer to similar parts throughout the drawings.

Referring to the drawings, A represents a frame or tripod constructed of standards B B and C, said standards being pivoted at 35 their outer ends to a metal cap, E, which is constructed with downwardly-projecting flanges having perforations, by means of which and suitable pins said standards are held in place loosely and allowed to expand or contract at 40 their inner ends. Cap E is also provided with a central perforation adapted to receive and hold an eyebolt, a, to which is secured a loose pulley, d⁴, over which passes rope d³, one end of said rope being attached to the 45 lower end of a strap clasping said pulley. The opposite end of said rope d³, passing over pulley d⁴, (which is provided with a suitable hook, to which the weight to be lifted is attached,) passes over roller d² and around 50 drum or cylinder d, to which it is secured. Drum or shaft d is journaled in plates e, secured to the outer faces of standards B B, and is provided with a gear-wheel, d', which is adapted or arranged to gear into a smaller

gear-wheel, b², which is secured to shaft b, 55 said shaft being provided with crank-arms b'.

The inner ends of standards B B are mortised into cross-bar D, on which they rest. A suitable tie-bolt and cross-bar, b³, is placed about midway between the inner and outer 60 ends of standards B B, the purpose of which is to stiffen and hold the parts in place. Between the standards, as shown suspended, is the weight b⁵.

The cap E is formed triangular in shape, 65 with angular openings e near the corners for the reception of the upper ends of standards B and C, said cap being provided with a top cover, f, from which project cross stiffening-ribs g, which are centrally perforated to receive bolt a.

The operation is as follows: Erect the tripod above the weight to be lifted, attach the hook on pulley d⁴ to the same, and turn the crank-arms b', when, by means of the small pinion or gear-wheel b⁴, acting on gear-wheel d', the rope d³ is wound around the drum d and the weight raised, when the tripod can be taken down and removed to another place to repeat 75 the operation.

By this construction a cheap and durable device is formed, by means of which rocks, 80 stumps, or heavy weights are easily handled, the simplicity and portability of the device being important features.

Having thus described my invention, what I claim, and desire to secure by Letters Patent, is—

1. A portable tripod consisting of three adjustable standards, two of which are secured by their inner ends to a cross-piece, 90 all of said standards being joined to a metal plate at their outer ends, said plate supporting tackle-blocks, with rope connection to winding mechanism secured to the outside of 95 said standards.

2. A tripod-derrick consisting of the standards B B and C, the cross-bar D, binding-rod b³, and the metal cap E, in combination with the eyebolt a, pulley-blocks d⁴, roller d², 100 drum d, shaft b, arms b', gear-wheels b² and d', caps e, rope d³, and the weight b⁵, all arranged and operated substantially as shown.

In testimony whereof I affix my signature in presence of two witnesses.

Witnesses: ANDREW B. MORRISON.

A. RUPPERT,

PHILIP F. LARNER.
